UNITED STATES PATENT OFFICE

HUGO F. SCHMIDT AND LOUIS JUNG, OF MILWAUKEE, WISCONSIN, ASSIGNORS TO
GUGLER LITHOGRAPHIC COMPANY, A CORPORATION OF WISCONSIN

OFFSET PROOF PRESS

Application filed March 14, 1929. Serial No. 346,841.

This invention relates in general to printing presses and more particularly to an offset proof press of the type which includes a stationary bed and a reciprocable carriage movable back and forth along the bed and carrying a rotatable printing cylinder overlying the bed and geared to fixed racks thereon so that upon movement of the carriage in one direction the cylinder rolls over the bed and first takes an impression from a printing plate positioned on the bed and then transfers this impression to a sheet of paper held on another plate of the bed.

In all prior presses of this type considerable difficulty has been encountered in producing high grade proofs, especially after the press has been in use for some time when, despite the exercise of care and expert skill in the operation of the press, more or less pronounced blurring or other distortion occurs in the proofs. These imperfections result largely from uncontrolled movements of the carriage and printing cylinder and although such movements are usually very slight they are sufficient to impair the proofs. Such uncontrolled movements are due principally to back lash or lost motion in the gearing which drives the carriage and the printing cylinder and to consequent uneven application of the drive to the opposite sides of the carriage and to the opposite sides of the printing cylinder whereby, during the printing run of the cylinder, it is slightly angled or twisted at different times, that is to say, one side of the cylinder will lag slightly behind the other in one phase of the operation and perhaps advance ahead of the other in another phase of the operation. This, of course, impairs the proof as the offset printing operation in this type of machine requires that the axis of the printing cylinder remain, during the entire printing run, at right angles to the longitudinal axis of the bed with which it has rolling contact. For the same reasons, with prior presses it has been difficult to obtain true registration in printing operations where successive impressions are superimposed one on the other.

One of the principal objects of the present invention is to simplify the construction and

operation of an offset proof press of this character while greatly improving the quality of the proofs produced thereby, in that blurring or other distortion is precluded and true registration is had. In brief, the present invention avoids the bad effects of back lash, lost motion, excessive clearances, or the like, in the drive of the carriage in the printing cylinder, and so uniformly and evenly drives the printing cylinder as to cause it to remain in proper relation to the printing bed during the printing run.

Another important object of the invention is to provide an offset proof press of this character which is durable in its construction and which will retain its advantages even when it has been in use for some time.

A further object is to provide a press of this character and having these advantages and capacities and which is convenient and safe in operation and easily manipulated to effect any of the desirable operations involved in the offset printing of proofs.

Other objects and advantages are to provide a press of compact construction in that the floor space required is the very minimum in proportion to the printing size; to provide an entirely unobstructed printing bed as the grippers and registering devices incorporated in the bed are inverted and located below the printing plane; to provide all-around accessibility to the blanket for cleaning or inspection since the cylinder is freely rotatable in one direction and without interfering with any of the other mechanism of the press relative to its driving means when it is positioned at either end of the press or at the center thereof; and to provide a press which minimizes the friction of all rotating parts by the use of roller bearings and which avoids the use of heavy machinery parts that must be moved whereby the motions and labor required of the operator are minimized, the impression time shortened, the speed increased, and the necessity of motor power obviated.

In carrying out these and other objects certain novel features are incorporated in the structure of the press and for the most part are in general as follows:

First, the novel carriage structure and mounting wherein the carriage frame members are connected by cross shafts extending transversely of the machine and supported on rollers rotatable on the cross shafts and riding in guide-ways of the frame of the bed, one of the cross shafts carrying means, such as eccentric, which may be manipulated for tilting the carriage to lift the printing cylinder and clear it of the printing bed, thus providing an emergency trip which may be used to advantage when it is desired to move the carriage through a printing run without the cylinder having printing contact with the bed.

Second, the novel means of driving the carriage including a hand crank having a one-way clutch with the drive shaft and an equalizer or differential between the drive shaft and helical drive gears thereon which mesh with fixed helical racks on the printing bed whereby the hand crank may be turned to apply a uniform drive force to both carriage members in such manner as to preclude twisting of the carriage and consequent angling of the cylinder. With this carriage drive, if the teeth of one helical drive gear engage the teeth of its rack prior to the engagement of the other helical gear teeth with their rack teeth, the differential or equalizer automatically functions to prevent the imparting of the positive driving force to either helical gear until the teeth of both exert uniform driving pressure on the teeth of their racks. Another advantage of the differential drive is that it makes it necessary to have absolute and exact alinement between the driving gears. By having the one-way clutch between the hand crank and the drive shaft, the hand crank is automatically thrown out at the end of the printing run and remains stationary during the return run thereby making it possible to speed up the return run without the hazard of a rapidly spinning hand crank. Whipping or twisting of the carriage which would result on the return run with a rapidly spinning hand crank is also avoided.

Third, the novel cylinder structure, mounting and drive wherein the cylinder is rotatable relative to its helical driving gears which mesh with the fixed racks of the bed, the cylinder being driven from the gears through a pair of one-way clutches or one-way driving connections associated with the cylinder driving gears and connected to the cylinder through an equalizer which insures the application of the driving force to the cylinder in such manner that the axis of the cylinder is maintained at right angles to the longitudinal axis of the bed as the cylinder is rolled over the bed. The cylinder is formed with a flat or gap which overlies the bed and is adjacent thereto at the end of the printing run and to preclude retrograde movement of the cylinder on the return run of the carriage, due to frictional drag of the one-way drive or other causes, a releasable locking device is organized with the cylinder and holds the same against reverse rotation on the return run. This locking device is interconnected with the means for tilting the carriage and clearing the cylinder of the printing bed so that whenever the cylinder is elevated the retrograde lock will be released to permit the cylinder to be freely rotated for cleaning, inspection, or other purposes. Further, in the cylinder construction, a novel blanket stretcher is incorporated which facilitates the placing of a uniform tension on the blanket thereby improving its capacity to effect the transfer printing operation in a superior manner. The tension is applied to the blanket stretcher through a plurality of adjusting devices such as thumb screws which permits the operator to sense or feel the tension applied to different portions of the blanket thereby insuring the placing of such tensioning force on the different parts of the blanket as is necessary to uniformly and properly tension the same.

Fourth, the embodiment in the structure of the printing bed and below the printing plane of novel sheet gripping and clamping means and of novel registering devices which facilitate the quick and accurate placement and securing of the print receiving surface. The sheet gripping devices are easily and quickly operated to grip or release the sheet with which they coat. By locating these devices below the printing plane, no obstruction is offered to the cylinder during its travel over the bed.

The invention also contemplates the omission of the differential in the drive for the carriage and this is done without losing the advantage of facilitating alinement of the gears, although, of course, in the absence of the differential drive exact uniformity is not always had in the application of the driving force to both sides of the carriage.

Another feature of advantage in the machine resides in its capacity for embodiment in either a right or left hand drive type without change of patterns. All that is required is a reversal of the drive shaft, its crank, the hand lever, the eccentric lift and the retrograde lock.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in side elevation showing a press embodying the present invention,

parts being broken away and shown in section for the sake of illustration;

Figure 2 is a view of the press in top plan;

Figure 3 is a view thereof in end elevation looking toward the left in Figure 1;

Figure 4 is a view in transverse vertical section taken on line 4—4 of Figure 1, parts being shown in elevation for the sake of illustration;

Figure 5 is a fragmentary view partly in side elevation and partly in longitudinal vertical section, the plane of the section being, for the most part, on line 5—5 of Figure 3, although certain parts of the machine in and adjacent to the plane of the section are broken away for the sake of illustration;

Figure 6 is a view in section taken in the plane of line 6—6 of Figure 5 and illustrating the differential drive for the carriage, parts being shown in elevation for the sake of illustration;

Figure 7 is a fragmentary detail perspective view having parts broken away and shown in section and illustrating the structure of the one-way clutch between the hand crank and the drive shaft;

Figure 8 is a fragmentary detail sectional view taken in the plane of line 8—8 of Figure 5 and showing how one of the transverse shafts is connected at each end to a carriage frame member;

Figure 9 is a fragmentary sectional view taken on line 9—9 of Figure 2;

Figure 10 is an enlarged fragmentary plan view of the parts shown in Figure 9;

Figure 11 is a view in transverse vertical section taken on line 11—11 of Figure 10 with parts shown in elevation for the sake of simplicity in illustration;

Figure 12 is a detail view of one of the registering devices and illustrating the same partly in side elevation and partly in section taken on line 12—12 of Figure 10;

Figure 13 is a sectional view taken on line 13—13 of Figure 12;

Figure 14 is a fragmentary detail view in top plan showing one of the laterally adjustable gauges or registering devices;

Figure 15 is a detail sectional view taken on line 15—15 of Figure 14;

Figure 16 is a fragmentary perspective view of certain of the elements shown in Figures 14 and 15;

Figure 17 is a fragmentary view in side elevation showing a modified form of drive for the carriage;

Figure 18 is a fragmentary view in horizontal section taken on line 18—18 of Figure 17 and also illustrating in top plan portions of the racks underlying the carriage; and

Figure 19 is a fragmentary view in horizontal section taken on line 19—19 of Figure 18, parts being shown in elevation for the sake of illustration.

Referring to the drawings, and more par-

ticularly to Figures 1 and 3, it will be seen that the machine comprises a base designated generally at 1 and made up of a pair of side members or base frames 2 which, if desired, may be fastened to a suitable foundation and which are rigidly connected in proper spaced relation by cross rods 3 having reduced extensions at their ends projecting through openings in the base frames and firmly clamped thereby by nuts and washers 4. The frame proper of the machine includes a pair of side frames 5, one side frame resting on each base frame and being securely bolted thereto by means of stud bolts 6 (see Figure 5).

The side frames 5 are rigidly held in proper spaced relation by cross members 7, 8 and 9, the cross members 7 and 9 being arranged at the ends of the side frames and the cross member 8 being arranged at the center thereof. Stud bolts 10 securely fasten these cross members to the side frames.

Bed plates 11 and 12 are positioned between the side frames 5 and are supported upon the cross members 7, 8 and 9, the plate 11 providing a support for the printing plate or printing surface and the bed plate 12 providing a support for the sheet or print receiving surface on which the proof is made. The bed plates 11 and 12 are of identical construction and are interchangeable. As shown in Figure 2, the bed plates 11 and 12 are formed with laterally directed guide lugs 13 engageable with the guide surface 5' formed on the side frames 5 whereby the side bed plates are held against any lateral movement although free to be adjusted vertically. The bed plates 11 and 12 are vertically adjusted and supported in any adjusted position by means of vertical screws 14 engaged with threaded openings provided therefor in lugs 15 integrally formed with bed plates. The upper ends of the screws are adapted to coact with a socket wrench or other suitable operating tool, and the lower ends thereof are smooth and bars or ledges 16 provided on the cross members 7, 8 and 9. As shown in Figure 2, four vertical screws 14 are provided for each bed plate, there being two lugs 15 at each end of each bed plate. The lugs 15 of the bed plates 110 located adjacent the center cross member 8 have their outer ends machined or ground to provide guiding and clamping surfaces engageable with similarly constituted surfaces on abutments 17 integral with the body of 115 the central cross member. When the desired vertical adjustment of the bed plates has been obtained by adjusting the vertical screws 14 the engaging surfaces of the lugs 15 and abutments 17 are forced into clamping engagement 120 by means of horizontal clamping screws 18 which are engageable with threaded bearings provided in the vertical webs 7' and 9' of the end cross members 7 and 9 and bearing against the ends of the lugs 15 located ad-

adjacent said screws 18. This secures the beds in any vertical adjustment but by loosening these screws 18 and appropriately adjusting the screws 14 the beds may be adjusted vertically to suit conditions.

A carriage, designated generally at 20, is supported on the side frames 5 for reciprocatory movement. To adapt the side frames 5 to support and guide the carriage, each has a longitudinal groove 21 opening through the outer surface thereof and also a longitudinal slot 22 through the floor of the groove, the groove 21 and slot 22 of one side member being transversely alined with the slot and groove of the other.

The carriage 20 includes a pair of carriage frame members 23, one such carriage frame member being located along the outside of each side frame member 5. The carriage frame members, which are similar in construction, are of approximately triangular form and at their lower corners are connected to the ends of horizontal shafts 24 and 25.

As shown in Figure 8, each end of the shaft 24 is snugly fitted in a bearing opening 27 provided therefor in one lower corner of each carriage frame member and the shaft 24 is held in these openings 27 and is fixed to the carriage frame members by means of stud bolts 28 threaded into the ends of the shaft 24 and bearing against a washer 29 which is clamped up against the margin of the opening 27.

As shown in Figure 4, the shaft 25 has its ends slightly reduced and snugly fitted in eccentrics 30 which are rotatably fitted in openings 31 provided in the other lower corner of each carriage frame member. The eccentrics 30 are fixed to the shaft 25 and are rotated therewith for the purpose of rocking or tilting the carriage but it is to be understood that during the ordinary printing operation the shaft 25 does not rotate. The fixing of the eccentrics 30 to the shaft 25 may be accomplished in any number of ways. As shown in Figure 4, each carriage frame 23 below its transverse bearing opening 31 is formed with a slot or opening 32 to permit a locating or set screw 33 to be threaded through the associated eccentric and into clamping engagement with the shaft 25. In addition to these screws 33, caps 34 and 35 are fitted over the ends of the eccentrics which, as shown in Figure 4, project slightly beyond the shaft and the carriage frames 23, the caps 34 and 35 having annular recesses which rather tightly receive the projecting ends of the eccentrics 30. Stud bolts 36 and 37 are extended through openings in the caps 34 and 35 and are threaded into the opposite ends of the shaft 25. Washers 36' and 37' are interposed between the heads of the stud bolts 36 and 37 and the caps 34 and 35 and when the bolts 36 and 37 are tightened up they clamp and rigidly secure the

caps 34 and 35 to the eccentrics 30 and the eccentrics 30 to the shaft 25.

The cap 34 is formed with a handle 38 which facilitates turning of the shaft and consequently of the eccentrics 30 to rock or tilt the carriage. The shaft 25 is held in any one of a plurality of angular adjustments by means of a spring projected detent 39 positioned in a socket in one of the carriage side frames 23 (see Figure 4) and co-operable with angularly spaced recesses 40 formed in the caps 34. The end of the detent 39 and the walls of the recesses 40 are beveled so that they serve merely to releasably hold the shaft 25 and its eccentrics 30 in position, thus preventing accidental displacement but permitting the operator to make the desired adjustment.

Rollers 41 and 45 are mounted on the shafts 24 and 25, respectively, and the rollers of each shaft are located adjacent the side frame members 23 of the carriage. The rollers 41 and 45 are of hardened steel and ride on the upper and lower walls of the guide grooves 21 on the printing and return run, respectively, of the carriage. At the ends of the guide grooves 21 stops 21' are provided for the rollers.

To permit the rollers 41 to turn freely, roller bearing assemblies 42 are interposed between the rollers 41 and the shaft 24 on which they are mounted (see Figure 8). It is to be noted that the inner race member of the roller bearing assembly 42 has one end abutting a shoulder 24' provided on the shaft 24. Between the other inner race member of the roller bearing assembly 42 and the carriage frame member 23 a washer 43 is interposed.

Roller bearing assemblies 46 are also interposed between the rollers 45 and their shaft 25 (see Figure 4) and are held in position just like the rollers 42 except that the washer 43' engaging the outer end of the inner race member of the roller bearing assembly 46 engages the eccentrics 30 instead of the carriage frame 23.

A printing or transfer cylinder designated generally at 50 is rotatably mounted on a shaft 51 supported by the upper portions of the carriage frame members. As shown in Figure 4, the ends of the shaft 51 are rotatably mounted in roller bearing assemblies 52 designed to take both radial load and axial thrust and fitted in bearing sockets 53 provided therefor in the upper corners of the carriage frame members. The ends of the shaft 51 project through the bearings 52 and into flanged caps 54 secured to the shaft by stud bolts 55 and loosely interfitted with openings 56 in the side frames of the carriage. Washers 57 received in recesses 57' in the carriage frame engage the caps 54 to exclude dust and dirt from the bearings.

The cylinder 50 includes an approximate-

ly cylindrical body portion 58 and integral end plates 59. The body 58 of the printing cylinder is formed with a gap or opening 60 flanked with inturned flanges 61 integral with the body of the cylinder. This provides a flat on the surface of the cylinder which functions as will be hereinafter more fully described and it also admits of the employment of a novel form of blanket stretcher to be hereinafter more fully described. The integral ends 59 of the cylinder are chambered as at 62 to receive roller bearing assemblies 63 whereby the cylinder is rotatably mounted on the shaft 51.

In order to rotate or roll the cylinder positively when the carriage is reciprocated along or over the beds, gear wheels 65 are provided and are secured to the shaft 51 by keys 66 and set screws 67. The gears 65 are positioned between the ends of the cylinder and carriage frame members, and they mesh with racks 68 secured to the side frames 5. In securing the racks 68 to the side frames 5, stud bolts 69 and dowel bushings 70 are provided, the dowel bushings being accurately machined to properly interfit with correspondingly formed openings provided therefor in both the racks 68 and the side frames 5 (see Figure 4). Thus, the dowel bushings hold the racks against any shifting horizontally and relieve the stud bolts 69 of shearing stresses to a large extent, the stud bolts 69 serving mainly to clamp the racks to the seats provided therefor on the side frames.

The teeth of the gear wheels 65 and of the racks 68 are of helical or herring-bone formation to provide for a smooth and easy translation of the reciprocatory motion of the cylinder into a rotary motion of the shaft 51 and back-lash and lost motion is reduced to a minimum. However, in order to eliminate the bad effects of any small amount of back-lash or lost motion that may exist and to avoid the problem of obtaining the mathematically precise alinement of the two gear wheels 65 essential for good printing, a compensating or equalizing driving means is provided between the gear wheels 65 and the cylinder 50. Another advantage of the helical gears employed for both the carriage and cylinder drives in this organization is the avoidance of gear streaks so common in proof presses as heretofore constructed.

In the form of the invention illustrated this drive comprises an equalizing bar 75 having a bearing 76 at its center portion pivotally supported on an inwardly directed radial stud 77 threadedly connected or otherwise secured to the body 58 of the cylinder (see Figures 4 and 5). A pin 78 or other suitable means prevents the bar from dropping off of the stud 77. At its ends the equalizer bar 75 carries fixed guide pins 79 on which driving pawls 80 are slidably fitted, the pawls 80 having sockets receiving the pins

79. Compression coil springs 81 are interposed between the ends of the bar 75 and shoulders on the pawls 80 and yieldably project the pawls 80. The pawls 80 coact with ratchet teeth 82 formed on rings 83 secured to the faces of the gear wheels 65 adjacent the cylinder 50. But one ratchet tooth is provided for each pawl as it is desirable to drive the cylinder when it is positioned in only one particular angular relation with respect to the gear wheel. The pawls and ratchet teeth are correspondingly beveled so that they provide a one-way clutch between the gear wheels and the cylinder thereby driving the cylinder when the carriage is propelled through its printing run but permitting the same to remain stationary on the return run of the carriage. Assuming that due to back-lash, lost motion, clearance, or any other reasons, the ratchet tooth 82 on one gear wheel 65 engages its pawl 80 before the ratchet tooth 82 of the other gear wheel 65 comes into engagement with its pawl. The motion of the gear wheel 65, which has its ratchet tooth 82 engaged with its pawl 80, will not operate to drive the cylinder 50 but will rock the equalizer bar 75 until the other pawl 80 is engaged with the ratchet tooth 82 of its gear 65, whereupon both ratchet teeth 82 exert uniform driving force upon the pawls 80 and consequently upon both ends of the cylinder 50. As both gear wheels 65 operate to apply the same driving force on the opposite ends of the cylinder any twisting of the cylinder, however slight, is prevented and further, one end of the cylinder is prevented from lagging behind the other during the printing run.

As pointed out, on the return run of the carriage the one-way clutches afforded by the pawls 80 and ratchet teeth 82 permit the cylinder to remain stationary. Means is provided to releasably lock the cylinder against retrograde or reverse turning movement during the return run of the carriage, and, as shown in Figures 2, 4 and 5, comprises a retrograde locking pawl 85 fixed to a shaft 86 rotatably mounted in one of the side frames of the carriage, said pawl 85 being cooperable with a notch 87 provided in one of the gauge rings 88 shrunk on the ends of the cylinder 50. These gauge rings 88 overlie accurately machined runners 88' formed on the side frames 5 and provide a convenient means whereby the clearance in between the printing cylinder and the bed may be gauged or determined. The notch 87 is so located that the locking pawl 85 automatically snaps therein at the end of a printing run at which time the flat of the cylinder is presented at the printing bed. On the return run of the carriage the drive of the gear wheels 65 is not positively transmitted to the cylinder and any drag that may be exerted tending to rotate the cylinder 50 reversely, is ineffective for this purpose due to the action of the locking

pawl 85. In order to bias the locking pawl 85 to engage its notch 87 and also to provide for the manual release of the locking pawl when desired, its shaft 86 is formed with a 5 crank arm 89, the outer end of which carries a swivel connector 90 through which a trip rod 91 is slidably fitted. An abutment 92 which may consist of a pair of nuts threaded on the upper end of the rod are engageable 10 with the swivel connector when the rod 91 is pulled downwardly whereby to rock the crank arm 89 and consequently its shaft 86 and pawl 85 out of engagement with the notch 87. The lower end of the swivel connector 15 is pivoted as at 93 to a crank arm 94 integrally formed with the cap 35 and thus turned with the shaft 25. A coil spring 96 encircles the trip rod below the swivel connector 90 and has one end bearing against the swivel 20 connector and has its other end bearing against a cross pin 97 carried by the trip rod. When the shaft 25 is in the position which it occupies when the carriage is in normal or printing relation to the bed, then the rod 91 is pushed upwardly through the swivel connector 25 90 and the spring 96 is compressed between the cross pin 97 and the swivel connector and tends to slide the swivel connector up along the trip rod and thereby press the 30 pawl against the adjacent gauge ring 88 so that it will snap into the notch 87 thereof when the notch comes around to the pawl. However, when the handle 38 is rotated to turn the eccentrics 30 and tilt the carriage 35 upwardly about the shaft 25 as an axis, the trip rod 91 is automatically pulled downwardly as its lower end is connected to the 40 crank arm 94 which, as described, is constrained to rotate with the shaft 25. This, as pointed out above, automatically releases the locking pawl 85 and permits the cylinder to be freely turned in one direction, the one-way clutches also taking part in this freedom afforded the cylinder. This permits 45 the cylinder to be cleaned, inspected, or manipulated for other purposes at any time in the printing run that the carriage is stopped.

Means is provided for propelling the carriage through its printing run and accomplishes this purpose while maintaining the carriage with its axis at right angles to the longitudinal axis of the printing bed, thereby insuring perfect registration and preventing blurring or other impairment of 50 the proof. In carrying out this purpose a driving shaft 100 is provided and has its ends mounted in roller bearings 101 designed to take both radial load and axial thrust and received in bearing sockets 101' provided therefor in the carriage frames 23 (see Figure 6). At one end the shaft 100 is provided with a cap 102 to exclude dust, dirt, and the like, from the adjacent bearing but freely rotatable relative 55 to the adjacent carriage frame member. A

hand crank 103 has its hub loosely mounted on the other end of the shaft 100 for relative rotary and sliding movement with respect thereto. A bushing 104 is interposed between the hub of the hand crank 103 and the 70 adjacent portion of the shaft 100. A washer 105 is secured by a stud bolt 106 to the shaft 100 and holds the bushing 104 on the shaft and prevents the crank 103 from sliding entirely off of the shaft. One end of the hub 75 of the hand crank 103 is formed with a clutch jaw 107 adapted to cooperate with a companion clutch jaw 108 keyed or otherwise suitably fixed to the shaft 100 just inwardly of the bushing 104. The jaw 108 also serves as a cap for preventing ingress of dust and dirt to the adjacent bearing 101. As shown in Figures 6 and 7, the clutch jaws 107 and 80 108 have engaging surfaces 107^a and 108^a and camming surfaces 107^b and 108^b and thus they are adapted to provide a one-way clutch between the hand crank and the drive shaft whereby the hand crank may be shifted inwardly to engage the clutch and then turned to positively propel the carriage on the printing run and yet is automatically thrown out and remains stationary on the return run of the carriage. This is an important advantage as a rapid spinning of 85 the hand crank on the return run of the carriage has always presented an element of hazard to the operators of presses of this type. The hand crank is releasably held in engaged or disengaged position by means of a spring pressed ball or detent 109 carried by the hub of the hand crank cooperable with spaced annular recesses 110 formed in the bushing 104.

Centrally, the drive shaft 100 is formed with an enlargement 100' having a diametrical opening receiving a differential pin 111, the ends of which project beyond the enlargement and provide stud shafts. Beveled planet pinions 112 are rotatably fitted on these studs and constantly mesh 110 with confronting driven bevel gears 113 fixed to sleeve shafts 114 mounted for free rotation on journals 114' provided therefor on the driving shaft. Helical or herringbone gear wheels 115 are fixed to the sleeve shaft 114 adjacent their outer ends and mesh with the racks 68. The differential or equalizer thus constituted is enclosed by a short cylindrical casing 116 secured by screws 116' to the outer ends of studs 111 which project through the planet pinions and the ends of the casing snugly fit against the peripheries of the gear wheels 113 although freely rotatable relative thereto. The differential pin 111 may be secured to the shaft 100 115 or the casing 116 may be relied upon to hold the differential pin against axial displacement. With this arrangement when the crank 103 is actuated to turn the drive shaft 100 it acts through the differen- 120 125 130 135 140 145 150

tial to turn the sleeve shafts 114 and consequently the crank wheels 115. If, due to excessive clearance, back-lash, lost motion, or other reasons, the teeth on one of the gear wheel 115 engage the teeth of its rack before the teeth on the other gear wheel 115 engages the teeth of its rack then the differential functions, slightly but effectively, to prevent transmission of the drive through the gear wheel 115 which is positively engaged with its rack teeth until the other gear wheel 115 has its teeth engaged with the teeth of its rack. Consequently, the driving force is always applied simultaneously and uniformly to both sides of the carriage and twisting and lagging of the carriage is precluded.

In accordance with the usual practice, a blanket 120 is wrapped around the periphery of the cylinder 50 and is secured and properly and uniformly tensioned on the cylinder 50 by means of a novel form of blanket stretcher. Each end of the blanket is clamped between a bar 121 of rectangular cross section and a bar 122 of L-shaped cross section, by clamping screws 123 extending through openings provided in the flange of the L-shaped bar 122 and through openings in the end of the blanket and threaded into openings found in the bar 121. The clamping bars 121 and 122 develop a high degree of friction with the ends of the blanket as they reversely bend the blanket between themselves. A clamping and equalizing plate 125 extends between and engages the L-shaped bars 122 and has flaring openings loosely receiving screws 126 anchored in a carrier bar 127 secured by stud bolts 128 to brackets 129 formed on the ends of the cylinder. Wing nuts 130 are threaded on the screws 126 and bear against the plate 125 so that when the wing nuts are tightened up the plate 125 and both sets of clamping bars 121 and 122 are forced inwardly. The clamping and equalizing action of the plate 125 serves to tighten up both ends of the blanket and to uniformly stretch and tension the same. Moreover, as the clamping plate bears against the angular clamping bar 122 adjacent the reverse bends 50 of the blanket ends, the blanket ends are more firmly gripped between the bars 121 and 122 by the pressures exerted by the clamping plate 125.

As previously indicated, the bed plate 11 supports a printing surface which may be the usual zinc plate designated at 135 in Figure 5. At one end, the bed plate 11 is formed with an integral downwardly inclined extension 136 to which the attaching portion of the zinc plate is clamped by a clamping bar 137 and clamping screws 138 which pass through the bar and the attaching portion of the zinc plate and which are threaded into the extension 136. Due to the offset or downward inclination of the extension 136,

the means for clamping the zinc plate to the bed is located entirely below the printing plane and thus no obstruction is presented in the path of the printing cylinder.

The bed plate 12 supports the print receiving surface which is usually in the form of a sheet of paper, or the like. To facilitate registration of the print receiving surface or sheet of paper and the accurate location thereof in the printing plane, a thin sheet of metal 135' rests flatly on the bed plate 12 and is clamped in position by means of a clamping bar 140 and clamping screws 141 coacting with a downwardly offset or inclined extension 142 of the printing bed 12. The surface of the metal sheet 135' is adapted to receive an impression of the crosses or other marks ordinarily employed in effecting registration of the print receiving surface or sheet and to carry out this function the surface of the plate or metal sheet 135' may be coated with white enamel such as white "Duco". With a plate of this character the cross marks on the zinc plate may be inked and the printing cylinder run over the inked cross marks to take an impression thereof on the blanket. Then, as the cylinder travels over the metal sheet 135', it transfers or impresses the crosses or registration marks on the metal sheet. The print receiving sheet has openings therethrough which are brought over the crosses or registration marks to properly register the print receiving surface. It is, of course, conventional to use these crosses in this way but it is entirely novel to utilize the transfer cylinder to take an impression of the crosses of the zinc plate and apply them to the surface which underlies the proof sheet or print receiving surface. In addition to this advantage the plate or metal sheet 135' may be raised or lowered vertically to locate it in the printing plane by shimming it up with filler sheets of paper or the like. This is advantageous as it saves the time that would otherwise have to be expended in resetting the bed plate 12.

The print receiving surface which, as indicated, is usually in the form of a sheet of paper, is clamped against the undersurface of a combined gripping and index plate 145, the top surface of which is located just below the printing plane. As shown to advantage in Figure 11, the plate 145 is supported on the central cross member 8 of the frame by means of spacing and supporting members 146 which have their lower ends engaging the cross member 8 and their upper ends enlarged and engaging the underside of the plate. Screws 147, which have their heads countersunk in the plate 145, pass through the plate and the members 146 and are threaded into the cross member 8 whereby to rigidly secure the plate 145 in position. For clamping the print receiving sheet up against the underside of the plate 145, gripping fingers,

designated generally at 148, are provided (see Figures 9 and 10), the gripping fingers being of resilient metal and each having one end bearing against a spacing block 149 and fastened through the block 149 to the plate 145 by means of screws or other suitable fastening devices 150. The inherent resiliency of the fingers 148 bias them to released position wherein their free gripping ends 148', which 10 are offset toward the plate 145, are spaced from plate 145 to admit of the free passage of the print receiving sheet to the space between themselves and the plate 145. When the sheet has its end edge positioned in between the 15 fingers 148 and the plate 145 the fingers are forced up against the paper and clamp the paper between themselves and the plate. This is accomplished by means of a cam shaft 151 having a plurality of cams 152 fixed 20 thereto, there being one cam 152 engaged with each gripping finger 148. As shown in Figures 9 to 11, the cam shaft extends transversely of the machine and of the gripping fingers and it is supported for rotary movement in bearings provided therefor in the supporting members 146. The cam shaft 151 is rotated from a finger lever 154 which is fixed to the outer end of a shaft 155 rotatably mounted in a bearing 156 secured to the underside of the plate 145. A beveled gear wheel 157 is fixed to the shaft 155 and meshes with a beveled gear wheel 158 fixed to the cam shaft 151. When the finger lever is in the position shown in Figures 9, 10 and 11, the cam shaft is so positioned that the gripping fingers 148 are released. By turning the finger lever 154 and the shaft 155 in counter-clockwise direction, as viewed in Figure 11, the cam shaft is turned to bring the highest point of the cams against the gripping fingers 148 and press these gripping fingers into sheet gripping position.

When the gripping fingers are in sheet gripping position the finger lever 154 is located in a horizontal position but has been rotated to 180° in a counter-clockwise direction from the position shown in Figure 11. Thus, in both positions of the finger lever it is located below the printing plane. For the 45 purpose of preventing the operator of the machine from inadvertently leaving the finger lever in an intermediate position in which it might project up above the printing plane and present an obstruction in the way of a printing cylinder, a self-acting spring biased toggle is associated with the finger lever. As shown in Figure 11, this toggle includes an arm 160 which may be formed as a continuation of the finger lever in which it is pivotally connected as at 160' to one end of the sliding link 161. The lower end of the link 161 slides through an opening provided therefor in a swivel pin 162, pivotally mounted on a bracket arm 163 which may be conveniently formed integral with the bearing 156

(see Figure 9). A coil spring 165 encircles the link 161 and has one end abutting a shoulder formed at the upper end of the link and has its other end abutting the swivel pin 162. The spring 165 is under compression and in the toggle arrangement shown biases the finger lever 154 to either one of its horizontal positions. If the finger lever is moved from the position shown in Figure 10 in a counter-clockwise direction for the first 90° of its movement the compression of the spring 165 is increased as such movement of the finger lever 154 slides the link 161 down through the opening of the swivel pin and thus shortens the distance between the ends 70 of the spring. After the finger lever passes the vertical position, further swinging movement in a counter-clockwise direction is accompanied by expansion of the spring 161 which, of course, tends to throw the finger lever to its other horizontal position. 75

To facilitate proper positioning of the print receiving surface the plate 145 is provided with longitudinally and transversely adjustable gauges.

The longitudinally adjustable gauges (see Figures 9, 10, 12 and 13) are two in number and are in the form of blocks 170 having beveled forward extensions 171 and provided with beveled guide pieces 172 fastened thereto by screws 173 and operating in longitudinal slots 174 formed in the plate 145. Graduations or scales 175 are provided on the plate 145 adjacent the slots 174 and facilitate precise adjusting of the gauges. The gauge blocks 170 are carried at the forward ends of rods 176 and the rearward ends of the rods are screw threaded as at 177 and pass loosely through spaced guides 178 fixed to the underside of the plate 145. Knurled thumb nuts 179, which are engaged with the threads of the rods 176, operate between the guides 178 and project up through slots or openings 180 formed in the plate 145. Obviously, by turning the nuts 179 in one direction the gauge blocks 170 are advanced and by turning the thumb nuts 179 in an opposite direction the gauge blocks 170 are retracted. 100

The transversely adjustable gauges include gauge plates 182 located one adjacent each end of the plate 145 and traveling across scales 183 provided along the forward edge of plate 145 adjacent each end thereof (see Figure 10). The gauges 182 are mounted on the plate 145 for transverse sliding movement and are releasably secured in any adjustment. The guiding and mounting of the gauges 182 is preferably effected by means of a guide member 184 (see Figures 14, 15 and 16), which has an upwardly directed flange 185 along its forward edge snugly fitted in a guide channel 186 provided in the underside of plate 145. The guide members 184 project rearwardly beyond the plate 145. 105 110 115 120 125 130 135 140

and each has an integral enlargement 187 spaced rearwardly from the plate 145 and designed to provide a fixed wedge and also to permit of the convenient connection of the gauge plate 182 to the guides 184. Thus, each gauge plate 182 is fastened to the enlargement 187 of its guide 184 by means of screws or rivets 188. And the forward wall of the enlargement 187 of each guide 184 is beveled at 187' to provide the fixed wedge structure. For releasably securing each gauge plate 182 in adjusted position a shiftable wedge 189 is provided and has its rearward end portion formed with a tapering or gradually inclined and enlarging portion 190 which coacts with the fixed wedge constituted by the inclined surface 187' of the guide 184. The wedge 189 is of L-shaped form and between the wider portion thereof and the enlargement 187 an expansible coil spring 191 is provided and tends to shift the wedge member 189 to the left as viewed in Figure 16, thereby causing the shiftable wedge to have binding engagement with the plate 145 and the enlargement 187 of the guide and consequently releasably securing the gauge plate 182 in adjusted position. By pressing the shiftable wedge 189 to the right, as viewed in Figure 15, the wedge surfaces 187 and 190 are disengaged and the gauge is freed or released for adjustment. The thumb and forefinger may be conveniently used to release the wedge 189 and shift the gauge.

In operation, the beds 11 and 12 are first adjusted to their proper vertical height and are clamped in such position. The zinc plate or other printing surface is then applied and clamped to the bed plate 11 and a sheet of paper or other print receiving surface is placed on the bed plate 12 and after being properly positioned with the aid of the registering devices or gauges, is clamped thereon by means of the gripping fingers 148 and the plate 145. The zinc plate having been inked, the operator grasps the hand crank 103 and pushes it in towards the carriage to engage the clutch jaws 107 and 108. The crank is then turned in a counter-clockwise direction, as viewed in Figure 1, and acting through the differential uniformly propels both sides of the carriage to the left, as viewed in Figure 1. As soon as the carriage starts in motion the gear wheels 65, due to their meshing with the fixed racks 68, are rotated and through the equalizing or compensating cylinder drive apply the driving force to the center of the printing or transfer cylinder thereby evenly driving the same without any twisting or angling. The blanket is thus caused to roll over the zinc plate and the impression is transferred from the zinc plate to the blanket. As the motion of the carriage and cylinder continue the carriage comes over the print receiving surface and the impression is trans-

ferred from the blanket to the print receiving surface. At the end of the printing run the flat of the cylinder lies over the bed of the press and the locking pawl 85 snaps into its notch 87 and these parts remain in this position and prevent retrograde movement of the cylinder during the return run of the carriage. In moving the carriage through the return run the operator grasps a handle 289 provided for this purpose and pushes the carriage back along the side frames. During the return run, the crank handle remains stationary as it is automatically thrown out by the camming surfaces of its clutch jaws 107 and 108. The cylinder also is held against rotation, as described, although it moves bodily with the carriage. If, at any time during the printing run, it becomes necessary or desirable to move the printing cylinder out of printing contact with the bed, this may be done by manipulating the lever 138 to tilt the carriage and release the retrograde lock that disengages the pawl 85 from its notch 87. Moreover, this throwing out of the cylinder does not interfere with motion of the carriage.

In Figure 17 to 19, inclusive, a modified form of mounting and drive is proposed for the printing cylinder. In all other respects the press is the same as that shown in Figures 1 to 16, inclusive, and the foregoing description applies thereto. Referring now to Figure 18, it will be seen that the printing cylinder 50 in the modified form of the invention is fixed to the inner ends of stud shafts 200 by means of nuts and washers 201 which force the inner tapered ends 200' of the stud shaft into tight engagement with tapered bearing openings 50a provided in the ends of the cylinder. The stud shafts also extend loosely through bushed openings in the hubs of gear wheels 202 meshing with the racks 68 of the printing bed. As shown, the hubs are somewhat extended on one side of the gear wheels 202 and the extended portions of the hubs project through roller bearing assemblies 203 supported in bearing recesses 204 provided on the carriage frames. The roller bearing assemblies 203 are designed to take both radial load and axial thrust and their inner race members have secure engagement with the extension of the hubs at the gear wheels 202 while their outer race members have tight gripping engagement with the walls of the bearing recesses in which they are positioned. The outer ends of the stud shafts are provided with washers 205 held in place by stud bolts 206 and operating to exclude dust from the bearing assembly. The equalizing or compensating one-way drive between the gear wheels 202 and the cylinder is exactly the same as in the other form of the invention. The modification also proposes the elimination of the differential in the carriage drive. This may be desired under some circumstances although usually the

differential would be employed in order to obtain a very accurate registration and is especially desirable where colors are superimposed one on the other or in other work where even a minute uncontrolled shifting of the cylinder or carriage will produce blurring or otherwise impair the proof. In the carriage drive shown in the modification, the drive shaft is designated at 210 and is rotatably mounted in roller bearings 211 provided in the frame of the carriage. Gear wheels 212 are keyed to the shaft 210 and mesh with the racks 68. A hand crank 103, exactly the same as that employed with the other form of the invention, is also employed here and has the same one-way clutch or one-way driving connection with the drive shaft.

From the foregoing it will be understood that the modified form of the invention is exactly the same in construction as the preferred form except that the differential in the carriage drive is omitted and that the cylinder driving gears are loosely instead of rotatably mounted on the shafts provided for mounting the printing cylinder on the carriage. The operation of the press with this modified cylinder mounting and modified carriage drive is precisely the same as that of the preferred form of the invention which has been hereinbefore described.

The invention claimed is:

1. An offset proof press of the character described comprising a bed, a carriage reciprocable along the bed, a traveling transfer cylinder rotatably mounted on the carriage and adapted to have rolling contact with the bed, a pair of fixed racks associated with the bed, a drive shaft rotatably mounted on the carriage, a pair of carriage driving gears meshed with the racks, means for transmitting the driving force from the drive shaft to said driving gears only when the teeth of both exert uniform driving pressure on the teeth of their racks, cylinder driving gears meshed with the racks and movable relative to the cylinder, and motion transmission means between said cylinder driving gears and said cylinder operable to transmit the driving force to the cylinder only when the teeth of both cylinder driving gears exert uniform driving pressure on the teeth of their respective racks.

2. A press of the character described comprising a bed, a carriage reciprocable along the bed, a cylinder rotatably mounted on the carriage and adapted to have rolling contact with the bed, fixed helical racks associated with the bed, a drive shaft rotatably mounted on the carriage, helical carriage driving gears meshed with the racks, means for transmitting the driving force from the drive shaft to said driving gears only when the teeth of both exert uniform driving pressure on the teeth of their racks, helical cylinder driving gears meshed with the racks and movable

relative to the cylinder, and motion transmission means between said cylinder driving gears and said cylinder operable to transmit the driving force to the cylinder only when the teeth of both cylinder driving gears exert uniform driving pressure on the teeth of their respective racks.

3. A press of the character described comprising a bed, a carriage reciprocable along the bed, a differential drive for the carriage, a cylinder rotatably mounted on the carriage and an equalized drive for the cylinder.

4. An offset proof press of the character described comprising a frame, a bed carried thereby, a carriage reciprocable along the bed, means for driving the carriage including racks fixed to the bed frame, and driving gears rotatably mounted on the carriage and meshed with the racks, a transfer printing cylinder rotatably mounted on the carriage, cylinder driving gears meshed with the racks and mounted on the carriage for rotation relative to the cylinder, and means for transmitting the drive from the cylinder driving gears to the cylinder and including a one-way driving connection cooperable with each driving gear and an equalizer between said driving connection and the cylinder.

5. An offset proof press comprising a bed, a cylinder, means for supporting the cylinder for rolling contact with the bed, and means for rotating the cylinder as it travels over the bed including driving gears, a one-way clutch cooperable with each driving gear and an equalizer carrying said clutches and connected to the cylinder.

6. An offset proof press comprising a bed, a traveling transfer cylinder cooperable with the bed, a pair of fixed racks, a pair of driving gears meshed with the racks and rotatable relative to the cylinder, and motion transmission means between the gears and the cylinder including an equalizer operable to transmit the driving force to the cylinder only when the teeth of both gears exert uniform driving pressure against the teeth of the racks whereby to propel the cylinder without angling or twisting.

7. An offset proof press comprising a bed, a traveling transfer cylinder cooperable with the bed, a pair of fixed racks, a pair of driving gears meshed with the racks and rotatable relative to the cylinder, an equalizer bar floatably connected to the cylinder, and means affording driving connection between the equalizer bar and the driving gears and permitting the bar to move relative to the cylinder to withhold the application of the driving force to the cylinder until the teeth of both gears exert uniform pressure on the teeth of their respective racks.

8. A press of the character described comprising a bed, a cylinder supported for rolling contact with the bed, and means for rotat-

ing the cylinder comprising driving elements and motion transmission means between the driving elements and the cylinder including an equalizer.

5 9. An offset proof press comprising a stationary bed, a traveling transfer cylinder, means for supporting the cylinder for rolling contact with the bed, and means for rotating the cylinder as it travels over the bed and including fixed racks, cylinder driving gears disposed adjacent the ends of the cylinder rotatable relative thereto and meshed with the racks, a one-way clutch associated with each driving gear, and an equalizer connecting the driven members of the clutches to the cylinder.

10 10. An offset proof press comprising a bed, a cylinder, means for supporting the cylinder for rolling contact with the bed, and means for rotating the cylinder as it travels over the bed including driving gears adjacent the ends of the cylinder and fixed racks on the bed with which the driving gears mesh, each driving gear having a ratchet, a pawl cooperable with each ratchet, an equalizer bar pivoted to the cylinder and carrying said pawls, and means for biasing the pawls to engage the ratchets.

15 11. A press of the character described comprising a bed, a carriage mounted on the bed for reciprocatory movement and carrying a cylinder adapted to have rolling contact with the bed and a drive for the carriage embodying a differential.

20 12. A press of the character described comprising a bed, a carriage reciprocable along the bed, a cylinder rotatably mounted on the carriage and adapted to have rolling contact with the bed, fixed racks associated with the bed, a drive shaft rotatably mounted on the carriage, carriage driving gears meshed with the racks, and means for transmitting the driving force from the drive shaft to said driving gears only when the teeth of both exert uniform driving pressure on the teeth of their respective racks.

25 13. A press of the character described comprising a bed, a carriage reciprocable along the bed, a cylinder rotatably mounted on the carriage and adapted to have rolling contact with the bed, fixed racks associated with the bed, a drive shaft rotatably mounted on the carriage, carriage driving gears meshed with the racks, sleeve shafts rotatably mounted on the drive shaft and to which said gears are fixed and a differential actuated from the drive shaft and driving the sleeve shaft.

30 14. A press of the character described comprising a bed, a carriage reciprocable along the bed, a cylinder rotatably mounted on the carriage and adapted to have rolling contact with the bed, fixed racks associated with the bed, a drive shaft rotatably mounted on the carriage, carriage driving gears meshed with the racks, sleeve shafts rotatably mounted on

the drive shaft and to which said gears are fixed, radial stud shafts constrained to rotate with the drive shaft, planet pinions rotatably mounted on the stud shafts, and driven gear wheels meshed with the planet pinions and fixed to the sleeve shaft.

35 15. An offset proof press of the character described comprising a frame, a bed carried thereby, a carriage reciprocable along the bed, means for driving the carriage including racks fixed to the bed frame, and driving gears rotatably mounted on the carriage and meshed with the racks, a transfer printing cylinder rotatably mounted on the carriage, cylinder driving gears meshed with the racks and mounted on the carriage for rotation relative to the cylinder, and means for transmitting the drive from the cylinder driving gears to the cylinder.

40 16. An offset proof press comprising a bed, a traveling transfer cylinder, a carriage on which the cylinder is rotatably mounted, said cylinder being adapted for rolling contact with the bed and having a flat or gap located adjacent the bed at the end of the printing run and during the return run, means for reciprocating the carriage, a one-way drive for rotating the cylinder as the carriage is moved through a printing run and means for preventing retrograde movement of the cylinder.

45 17. An offset proof press comprising a bed, a traveling transfer cylinder, a carriage on which the cylinder is rotatably mounted, said cylinder being adapted for rolling contact with the bed and having a flat or gap located adjacent the bed at the end of the printing run and during the return run, means for reciprocating the carriage, driving elements geared to the bed so as to be rotated when the carriage is reciprocated, a one-way driving connection between the driving elements and the cylinder for rotating the cylinder during the printing run, and pawl and ratchet means between the carriage and the cylinder for holding the cylinder against retrograde movement during the return run while leaving the same free to rotate forwardly during the printing run.

50 18. An offset proof press comprising a bed, a traveling transfer cylinder, a carriage on which the cylinder is rotatably mounted, said cylinder being adapted for rolling contact with the bed, means for reciprocating the carriage, a one-way drive for rotating the cylinder during printing runs, means for preventing retrograde movement of the cylinder, means for throwing the cylinder out of printing relation to the bed, and a release for the means which prevents retrograde movement.

55 19. An offset proof press comprising a bed, a traveling transfer cylinder, a carriage on which the cylinder is rotatably mounted, said cylinder being adapted for rolling contact

- with the bed and having a flat or gap located adjacent the bed at the end of the printing run and during the return run, means for reciprocating the carriage, driving elements 50 geared to the bed so as to be rotated when the carriage is reciprocated, a one-way driving connection between the driving elements and the cylinder for rotating the cylinder during the printing runs, a retrograde lock 55 for holding the cylinder against reverse movement during return runs, a throwout for the cylinder, and a release for the retrograde lock interconnected with and actuated by the throwout whereby the cylinder may be freely 60 rotated in any phase of the operation when out of contact with the printing bed.
20. An offset proof press comprising a bed, a carriage reciprocable along the bed, a traveling transfer cylinder rotatably supported 65 on the carriage and having a flat or gap disposed adjacent the bed at the end of each printing run and during each return run, means for supporting and guiding the carriage to constrain it to maintain the cylinder 70 in such position as to be adapted to have rolling contact with the bed during each printing run, a throwout associated with said supporting means and operable to tilt the carriage to elevate the cylinder out of printing 75 relation to the bed in any phase of the operation, a drive for rotating the cylinder during each printing run, holding means for preventing rotation of the cylinder during each return run, and a release for the holding means.
30. 21. An offset proof press comprising a bed, a carriage reciprocable along the bed, a traveling transfer cylinder rotatably supported 80 on the carriage, means for supporting and guiding the carriage to constrain it to maintain the cylinder in such position as to be adapted to have rolling contact with the bed during each printing run, and a throwout associated with said supporting means and operable to tilt the carriage relative to its 85 supporting means to elevate the cylinder out 90 of printing relation to the bed.
22. An offset proof press comprising a bed, a carriage reciprocable along the bed, a traveling transfer cylinder rotatably supported 95 on the carriage and having a flat or gap disposed adjacent the bed at the end of each printing run and during each return run, means for supporting and guiding the carriage to constrain it to maintain the cylinder 100 in such position as to be adapted to have rolling contact with the bed during each printing run, a throwout associated with said supporting means and operable to tilt the carriage to elevate the cylinder out of printing 105 relation to the bed in any phase of the operation, a one-way drive for rotating the cylinder during printing runs, a retrograde lock 110 for preventing reverse rotation of the cylinder during return runs, and a release

for the lock automatically operated by the throwout.

23. An offset proof press comprising a bed, a traveling transfer cylinder, a carriage on which the cylinder is rotatably mounted, 115 said cylinder being adapted for rolling contact with the bed, means for reciprocating the carriage, a one-way drive for rotating the cylinder during printing runs, a throwout for elevating the cylinder out of printing relation to the bed, a ratchet on the cylinder, a pawl mounted on the carriage and biased to engage the ratchet to prevent reverse turning of the cylinder, and a release actuated from the throwout and cooperable with the pawl to disengage it from the ratchet when the cylinder 120 is elevated out of operating relation to the bed.

24. An offset proof press comprising a bed, a printing cylinder, a carriage on which the printing cylinder is rotatably mounted, means for normally supporting and guiding the carriage in printing relation to the bed and operable to tilt the carriage upwardly, 125 said cylinder being adapted for rolling contact with the bed and having a flat or gap overlying the bed at the end of the printing run and during the return run, means for reciprocating the carriage, means for rotating the cylinder as the carriage is moved through a printing run while permitting the same to remain stationary during the return run and comprising driving elements geared to the bed so as to be rotated when the carriage 130 is reciprocated, a one-way driving connection between the driving elements and the cylinder, pawl and ratchet means between the carriage and the cylinder for holding the cylinder against retrograde movement while leaving the same free to rotate forwardly during the printing run, and a release for the pawl and ratchet means interconnected with the means for tilting the carriage so as to be automatically operated when the carriage is 135 tilted.

25. In a press of the character described, a bed, a carriage including a carriage frame member at each side of the bed, means for connecting the carriage frame members and supporting the carriage for movement over the bed including cross shafts connecting the carriage frame members and carrying rollers, eccentrics on one of the shafts cooperable with the carriage frame members whereby the carriage may be tilted and a printing cylinder mounted on the carriage and adapted to have rolling contact with the bed.

26. In a press of the character described, a rotatable cylinder, a one-way drive therefor, a retrograde lock for preventing reverse rotation of the cylinder, a throwout for the cylinder, a release for the retrograde lock, and common means for actuating the throwout and the release.

27. An offset proof press of the character

described comprising a frame having a bed and also having guide-ways therein, a carriage reciprocable over the bed, cross shafts connected to the carriage and having rollers rotatably mounted thereon and operating in the guide-ways, eccentrics fixed to one of the cross shafts and cooperable with the carriage for tilting the same, a printing cylinder mounted on the carriage and adapted for 10 rolling contact with the bed, and means for driving the carriage and the cylinder.

28. An offset proof press comprising a frame having guide-ways, a printing surface and a print receiving surface supported on 15 said frame, a carriage including carriage frame members adjacent the sides of the frame, cross shafts extending between said carriage frame members, rollers rotatably mounted on the cross shafts and operating in 20 the guide-ways of the frame, eccentrics between one of said cross shafts and the carriage frame members, means for turning the cross shaft having the eccentrics whereby to tilt the carriage when desirable, and a printing cylinder rotatably mounted on the carriage and adapted for rolling contact with 25 said surfaces.

29. An offset proof press comprising a frame having guide-ways, a printing surface and a print receiving surface supported on 30 said frame, a carriage including carriage frame members adjacent the sides of the frame, cross shafts extending between said carriage frame members, rollers rotatably mounted on the cross shafts and operating in 35 the guide-ways of the frame, eccentrics between one of said cross shafts and the carriage frame members, means for turning the cross shaft having the eccentrics whereby 40 to tilt the carriage when desirable, a printing cylinder loosely mounted on the carriage, means for causing the printing cylinder to have rolling contact with said surfaces during the printing run of the carriage, said 45 cylinder having a flat disposed adjacent said surfaces at the end of the printing run and during the return run of the carriage, means for holding the cylinder against retrograde 50 movement during the return run and a release for the holding means automatically operated when the carriage is tilted.

30. A printing press of the character described including a frame having a bed, a carriage supported on the frame for reciprocatory movement therealong, means for reciprocating the carriage including helical racks fixed to the frame, helical driving gears mounted on the carriage and meshed with 55 the racks, means for rotating said gears including a drive shaft and a differential actuated from the drive shaft and having its driven gears connected to the helical gears, a printing cylinder rotatably mounted on the carriage, and helical drive gears meshed with 60

the racks and having a driving connection with the cylinder.

31. A printing press of the character described including a frame having a bed, a carriage supported on the frame for reciprocatory movement therealong, means for reciprocating the carriage including helical racks fixed to the frame, helical driving gears mounted on the carriage and meshed with the racks, means for rotating said gears, a printing cylinder rotatably mounted on the carriage, and helical drive gears meshed with the racks and having an equalized driving connection with the printing cylinder. 70

32. An offset proof press comprising a printing bed having a printing surface and a print receiving surface, an offset printing cylinder adapted to have rolling contact with the surfaces of the printing bed, a carriage upon which the cylinder is rotatably mounted, means for supporting the carriage for reciprocatory movement along the bed, means for driving the carriage including gear wheels rotatably mounted on the carriage and racks fixed to the bed and meshed with the gear wheels and means for rotating the printing cylinder and comprising gear wheels rotatably mounted on the carriage meshing with the racks and having driving connection with the cylinder. 75

33. A press of the character described including a bed, a reciprocable carriage carrying a cylinder adapted to have rolling contact with the bed, and means for driving the carriage including a drive shaft, a hand crank, and a one-way clutch between the hand crank and the drive shaft. 80

34. A press of the character described including a bed, a carriage mounted on the bed for reciprocatory movement and carrying a cylinder adapted to have rolling contact with the bed, means for driving the carriage including a drive shaft, a hand crank, and cooperable clutch jaws between the hand crank and the drive shaft engageable to permit the hand crank to be turned to actuate the drive shaft in one direction and having camming surfaces for throwing out the hand crank upon reverse movement of the drive shaft. 105

35. In a printing press of the character described, a frame, a printing bed, vertical screws coacting with the bed and with the frame to support the bed on the frame in various vertical adjustments, cooperating guide means between the sides of the bed and the frame for constraining the bed to vertical movement, cooperable abutments integral with one end of the bed and the frame, and clamping means engageable with the other end of the bed for forcing said abutments into engagement. 110

36. In an offset proof press of the type having a reciprocable carriage and a rotating cylinder mounted on the carriage and movable bodily with the carriage as well as rotated 120

during a printing run, a bed which includes a bed plate adapted to support a printing surface and a bed plate adapted to support a print receiving surface, the bed plate which is adapted to support the print receiving surface having a metal sheet releasably secured thereto and adapted to receive registration marks transferred thereto from the printing surface of the cylinder, said metal sheet being 10 free of its bed plate except at one end whereby it is adapted to be shimmed up by filler sheets to locate it in proper relation to the printing plane.

37. A press comprising a bed, a cylinder 15 supported for rolling contact with the bed, and a drive for rotating the cylinder and embodying an equalizer functioning to maintain the cylinder in true printing relation to the bed throughout the printing run.

38. An offset proof press of the character described comprising a bed, a carriage reciprocable along the bed, a traveling transfer cylinder mounted on the carriage and adapted to have rolling contact with the bed, and 25 a drive for the carriage having means for applying a balanced and uniform driving force to both sides of the carriage.

39. In a press of the character described, a bed, a carriage movable over the bed, a printing cylinder rotatably mounted on the carriage and adapted to have rolling contact with the bed, rollers connected to the carriage, means associated with the bed and constituting guide-ways for the rollers, and 35 means interposed between at least one of said rollers and said carriage for tilting the carriage to clear the cylinder of the bed.

In witness whereof, we hereto affix our signatures.

40 HUGO F. SCHMIDT.
LOUIS JUNG.
